MATERIAL HANDLING DEVICE

Ralph R. Kelley, Dearborn, Mich.

Application July 9, 1956, Serial No. 596,782

4 Claims. (Cl. 294—103)

The present invention relates generally to material handling devices, and particularly to improvements in a device for handling coils of metal.

Prior to the present invention, a simple and efficient device has been sought which could work with a crane to lift and manipulate coils of metal. Strip steel is supplied in coils usually weighing several thousand pounds. These coils must be unloaded from the transporting trailer which delivers the same. The coils are then stored in a suitable location. They are usually manipulated at a later time onto a coil reel which feeds the strip steel to a device such as a slitter. During these operations a chain is disposed on the coil for engagement by the crane hook. This is an inefficient and risky makeshift way of handling coils of metal.

Devices have been proposed for solving this problem of material handling, but they have been complex and costly in construction.

It is a principal object of the present invention to provide a material handling device, particularly adapted for handling coils of metal, which is simple in construction and positive and efficient in operation.

It is another object of the present invention to provide a balanced device adapted for use with a crane, which device will effectively lift and manipulate coils of metal into various positions.

It is a further object of the present invention to provide a material handling device, particularly adapted for handling coils of metal, which requires minimum manual operation.

It is another object of the present invention to provide a material handling device, particularly adapted for use with coils of metal, which utilizes the weight of the object being handled to lock the object in place.

Other objects of this invention will appear in the following description and appended claims, reference being had to the accompanying drawings forming a part of this specification wherein like reference characters designate corresponding parts in the several views.

In the drawings:

Fig. 1 is a side elevation of a coil handling mechanism embracing the first embodiment of the present invention, a coil being shown in the horizontal position in phantom.

Fig. 2 is a view similar to Fig. 1, and the coil is shown in the vertical position.

Fig. 3 is a side elevation of a coil handling mechanism embracing the second embodiment of the present invention.

Fig. 4 is a side elevation of a coil handling mechanism using the third embodiment of the present invention.

Before explaining the present invention in detail, it is to be understood that the invention is not limited in its application to the details of construction and arrangement of parts illustrated in the accompanying drawings, since the invention is capable of other embodiments and of being practiced or carried out in various ways. Also, it is to be understood that the phraseology or terminol-

ogy employed herein is for the purpose of description and not of limitation.

Referring to the drawings, Fig. 1 shows a coil handling mechanism using one embodiment of the present invention. The device comprises a track member 10 having an upper rail 12 and a lower rail 14. Similar rails are provided on the opposite side of the track member. A balance member 16 is provided at the top of the device. The balance member is provided with wheels 18 and 20 which are disposed on the axles 22 and 24 respectively. These wheels engage the rails 12 and 14 on the track member 10. Similar wheels are provided on the opposite side of the track member.

A flange 26 is affixed to one end of the track member 10. A threaded shaft 28 is journaled in the flange 26 and extends through the balance member 16 in threaded engagement therewith. A hand wheel 30 is disposed on one end of the shaft 28, and a handle 32 is affixed to the hand wheel. Rotation of the hand wheel 30 will move the balance member along the track member 10 to balance the device when it performs a lifting function. An opening 34 is provided in the balance member 16 to accommodate a crane hook (not shown).

A vertical support member 36 is affixed to the track member 10. A trunnion 38 is formed at the bottom of the vertical support member 36. The trunnion is disposed at a 45 degree angle with respect to the vertical support member 36. A clamp bracket 40 is provided adjacent the trunnion 38. The clamp bracket 40 includes a stub shaft 42 which extends within the trunnion 38 in rotatable engagement therewith. The stub shaft is retained in the trunnion by any suitable means such as the bolt 44 which extends through the open end of trunnion 38 into a threaded opening in the end of stub shaft 42. A washer 46 is disposed between the head of the bolt 44 and the end of trunnion 38.

Disposed through clamp bracket 40 is an adjusting mechanism 47. This adjusting mechanism comprises a vertical slide member 48 which has a clamp jaw 50 affixed to the lower end thereof. Journaled in the slide member 48 is a threaded shaft 51 which engages a threaded lug 52 in the clamp bracket 40. A hand wheel 54 having a handle 56 thereon is affixed to the top end of threaded shaft 51. Rotation of the hand wheel 54 will raise and lower the clamp jaw 50 with respect to the clamp bracket 40.

In operation, a crane hook is inserted through the opening 34 in balance member 16. Hand wheel 54 is rotated to engage a coil of steel such as the one shown in phantom at 56 upon jaw 50. As hand wheel 54 is rotated, the shaft 51 is rotated within the threaded lug 52. This causes the clamp jaw 50 to move upward toward the clamp bracket 40 until the coil of steel is engaged, as shown in Fig. 1. The crane is then lifted slightly until it is seen whether or not the rig is in balance. If it is not, the hand wheel 30 is rotated, moving the balance member 16 back or forward until the proper balance is established. The crane can then lift the clamping device 60 and coil of steel to the desired position.

If it is desired to handle coils in the vertical position, the clamp bracket 40 is turned to the position shown in Fig. 2 by rotating the bracket and accompanying stub shaft 42, the stub shaft rotating within the trunnion 38. Also if the coil is first lifted in one position, it can be turned to a different position while in the clamp by rotating the clamp bracket 40.

The second embodiment is shown in Fig. 3 of the drawings. In this embodiment, electric motors 130 and 154 are substituted for the hand wheels 30 and 54 shown in Fig. 1. Also an electric motor 144 is affixed to the stub shaft 142 of the clamp bracket 140. Suitable electrical

controls, not shown, will energize the motor 130 to move the balance member 116 back and forth on the threaded shaft 128 to establish balance. Electrical controls may also energize the motors 154 and 144 to perform the clamping actions and pivoting actions respectively. Any well known arrangement of electrical controls can be used, and so such controls are not shown in the drawings. The use of electrical motors and controls adds to the cost of the device, but may render it automatic in operation.

Fig. 4 of the drawings shows another embodiment wherein the weight of the object being lifted acts to lock the clamping jaws in place. In this arrangement, a guiding eyelet 258 and a pulley 260 are affixed to the horizontal member 210. A pulley 262 is affixed to the vertical member 236, and a pulley 264 is affixed to the trunnion 238. A lifting cable 266 is disposed along these pulleys and extends through an opening in the center of the stub shaft 242 which extends down through the bottom of the clamping bracket 240. The cable then extends over pulley 268 and is affixed to clamping bracket 240. When a coil of metal is disposed between the clamping jaw 250 and the clamping bracket 240, a lifting force is applied to the upper end of the cable 266 by a crane. The lifting force pulls against the weight of the coil, and this lifting force is transferred through the cable 266 to tightly engage the jaws 240 and 250 with the coil. A balancing mechanism such as shown in Figs. 1-3 can also be used with this embodiment.

From the foregoing description, it will be apparent that I have provided a novel and efficient material handling device which is simple in arrangement and operation.

Having thus described my invention, I claim:

1. A material handling device, particularly adapted for use with a coiled workpiece such as a coil of metal, comprising a substantially L-shaped frame member which includes a horizontal leg and a vertical leg; a trunnion in the lower portion of said vertical leg, the axis of said trunnion being disposed at substantially a forty-five degree angle relative to said vertical leg; a horizontal clamp bracket having a shaft thereon disposed in rotatable engagement with said trunnion; a vertical slide member having a horizontal clamp jaw rigidly affixed thereto, said clamp jaw being slidable on said slide member; means for moving at least one of said clamp members so that the workpiece is gripped firmly between the said clamp members; said clamp members being turnable to a vertical position about the axis of said trunnion so that the workpiece can be placed in either a horizontal or vertical position; and means on said horizontal leg to permit said frame member to be secured to a lifting mechanism such as a crane.

2. A material handling device, particularly adapted for use with a coiled workpiece such as a coil of metal, comprising a substantially L-shaped frame member which includes a horizontal leg and a vertical leg; a trunnion in the lower portion of said vertical leg, the axis of said trunnion being disposed at substantially a forty-five degree angle relative to said vertical leg; a horizontal clamp bracket having a shaft thereon disposed in rotatable engagement with said trunnion; a vertical slide member having a horizontal clamp jaw rigidly affixed thereto, said clamp jaw being slidable on said slide member; a guide affixed to said slide member adjacent said clamp

members, said clamp members being turnable to a vertical position about the axis of said trunnion so that the workpiece can be placed in either a horizontal or vertical position; a flexible cable connected at one end to said clamp bracket and extending around said guide to a point adjacent the free end of the horizontal leg on said frame; and the free end of said flexible cable secured to a lifting device such as a crane.

3. A material handling device, particularly adapted for use with a coiled workpiece such as a coil of metal, comprising a substantially L-shaped frame member which includes a horizontal leg and a vertical leg; a trunnion in the lower portion of said vertical leg, the axis of said trunnion being disposed at substantially a forty-five degree angle relative to said vertical leg; a horizontal clamp bracket having a shaft thereon disposed in rotatable engagement with said trunnion; a vertical slide member having a horizontal clamp jaw rigidly affixed thereto, said clamp jaw being slidable on said slide member; means for moving at least one of said clamp members so that the workpiece is gripped firmly between the said clamp members; said clamp members being turnable to a vertical position about the axis of said trunnion so that the workpiece can be placed in either a horizontal or vertical position; and means for affixing the horizontal leg of said frame member to a lifting mechanism such as a crane, said means being movable along the horizontal leg of said frame member to balance the material handling device.

4. A material handling device, particularly adapted for use with a coiled workpiece such as a coil of metal, comprising a substantially L-shaped frame member which includes a horizontal leg and a vertical leg; a trunnion in the lower portion of said vertical leg, the axis of said trunnion being disposed at substantially a forty-five degree angle relative to said vertical leg; a horizontal clamp bracket having a shaft thereon disposed in rotatable engagement with said trunnion; a vertical slide member having a horizontal clamp jaw rigidly affixed thereto, said clamp jaw being slidable on said slide member; means for moving at least one of said clamp members so that the workpiece is gripped firmly between the said clamp members; said clamp members being turnable to a vertical position about the axis of said trunnion so that the workpiece can be placed in either a horizontal or vertical position; means on the horizontal leg of said frame member for securing said frame to a lifting mechanism such as a crane; and adjusting means for moving said fastening means along said horizontal leg to balance the material handling device.
